UNITED STATES PATENT OFFICE

167,755

RADIANT HEATER

Martin L. Kornstein, Jackson Heights, N. Y.

Application December 28, 1951, Serial No. 17,845

Term of patent 7 years

(Cl. D81—10)

To all whom it may concern:

Be it known that I, Martin L. Kornstein, a citizen of the United States, residing at 76-09 34th Avenue, Jackson Heights, New York, have invented a new, original, and ornamental Design for a Radiant Heater, of which the following is a specification, reference being had to the accompanying drawing, forming part thereof, in which:

Fig. 1 is a perspective view taken from the front of a radiant heater embodying my new design;

Fig. 2 is an end elevation thereof; and

Fig. 3 is a back elevation of the radiant heater shown in Figs. 1 and 2.

I claim:

The ornamental design for a radiant heater, as shown.

MARTIN L. KORNSTEIN.
